James C. Harris
INVENTOR.
BY John M. Spellman

ATTORNEY

UNITED STATES PATENT OFFICE.

JAMES C. HARRIS, OF DALLAS, TEXAS.

TOY GUN.

Application filed November 6, 1922. Serial No. 599,264.

To all whom it may concern:

Be it known that JAMES C. HARRIS, a citizen of the United States, residing at Dallas, in the county of Dallas and State of Texas, has invented certain new and useful Improvements in Toy Guns, of which the following is a specification.

This invention relates to toy guns and refers especially to a toy for shooting rubber bands, said toy having one or a number of triggers, one behind the other, encased and guided by a metal means surrounding a wooden stock, each trigger consisting of a sliding pin which is applied to a swinging lever, said lever being supported from a pin set in the walls of that portion of the toy corresponding to a breech. This lever when raised by operation of the sliding pin, releases a rubber band stretched over the muzzle of the gun and pulled back into a vertical notch cut in the breech of the gun behind the point of support of the lever; said trigger so spaced at the point of rest that the lever element, when the trigger is pulled, is not affected by the position of the lever behind it and adjacent to it.

The rear trigger, or the one nearest the butt of the gun, must be pulled first, as the rubber band it releases holds down all the other bands in the respective notches behind the other triggers. The other triggers may be pulled in turn, in a direction toward that part of the toy corresponding to the muzzle of the gun.

A new and novel feature of my invention is an auxiliary attachment for lengthening the barrel of the gun, allowing larger rubber bands to be used and greater range to be obtained, said attachment consisting of a base of wood, tapered to extend beyond the basic barrel of the gun, conforming to and aligned with it, and held in place by means of a metal socket, slipping snugly over the end of the barrel.

Another feature is the space cut in the lower edge of butt of gun, for holding spare rubber bands, enclosed by a hinged metal means locked by a spring.

The metal means wherein the trigger element is operated is secured to the body of the gun by nails, screws, bolts or rivets.

Another feature of my invention is the combination of noiselessness and safety of operation with durability of construction.

The operating principles of the invention will be more clearly understood taken in

connection with the drawings attached hereto, as follows:

Figure 1 is a top or plan view of the invention. 60

Figure 2 is a side elevational view of the invention.

Figure 3 is a side elevational view of that portion of Figure 2 comprising the trigger mechanism with a portion of the enclosing 65 metal case cut away to show the operation of said mechanism.

Figure 4 is a side elevational view of the barrel, with the extension fixed thereto.

Figure 5 is a cross sectional view of the 70 assembly of the trigger mechanism showing the position of the trigger as it is pulled.

Figure 6 is a side elevational view of the pocket for extra rubbers shown in Figure 2, with a portion cut away to show the interior 75 and the position of the extra bands.

In Figure 1, frame 1 is shown with the extension 2 affixed by means 3. Rubbers are shown in place, stretched from end of barrel to notches in trigger mechanism 80 sheath 12.

In Figure 2, the frame 1 is shown, the pocket cover 4 in place over the pocket and locked by spring 5. The sheath 12, with the notches above, and the trigger pins below, is 85 shown with the rubber bands "A" stretched as in Figure 1. The extension 2 is held in place by means 3 on frame 1.

In Figure 3, the operation of the trigger mechanism is shown, triggers 9 and 11 being in a passive position, and levers 6 and 8 also passively hanging from their supporting elements. Trigger 10 is shown in action applied to lever 7, causing lever 7 to be lifted, releasing the rubber band resting 95 thereon. The metal means 13 and 14 are secured to the wooden frame and slotted to allow the free passage of the trigger pins; the frame included therein is also slotted to coincide with the slots in the metal means. 100

Figure 4 shows the detail of the attachment of extension 2 to frame 1 by means of means 3.

In Figure 5, the trigger 10 is shown applied to lever 7, raising it to release the rubber band. 12 represents the metal sheath, 105 13 and 14 the pin guiding metal strips.

What is claimed is:

1. A toy of the character described comprising a wooden frame unit, consisting of a butt, stock and barrel, an assembly of triggers, said assembly consisting of a series of 110

push pins, one behind the other, sliding through openings in the breech portion of the frame and in the sheath enclosing it; levers attached to the upper portion of the breech and encased therein, to each of which the push pin is applied, each trigger mechanism being separate and apart from the other, vertical notches in the upper portion of the breech behind each lever, rubber bands attached from said notches to and over the end of the barrel, and a pocket within the butt portion of the frame, a metal cover encasing said pocket and a spring securing the cover in place, said toy to be used for shooting rubber bands.

5 10 15

2. A toy of the character described, for

shooting rubber bands, a frame of wood in one unit, comprising a butt, a stock and a barrel combination, a pocket within the butt and encased therein by metal cover, a trigger mechanism secured to stock by metal means partially surrounding same; said sheath notched vertically in its upper surface, a barrel, an attachment to a barrel, and rubber bands stretched over the end of the barrel and pulled back over the respective notches in the metal sheath encasing the breech.

20 25

In testimony whereof I have signed my name to this specification.

JAMES C. HARRIS.
